UNITED STATES PATENT OFFICE.

SAMUEL S. EVELAND, OF PHILADELPHIA, PENNSYLVANIA.

LIFTING-JACK

No. 811,136.

Specification of Letters Patent.

Patented Jan. 30, 1906.

Application filed August 23, 1904. Serial No. 221,847.

To all whom it may concern:

Be it known that I, SAMUEL S. EVELAND, a citizen of the United States, and a resident of Philadelphia, in the county of Philadelphia and State of Pennsylvania, have invented certain new and useful Improvements in Lifting-Jacks, of which the following is a specification.

Lifting-jacks are subjected to tremendous loads, and it is advantageous that their parts should move with as little friction as possible. Balls have proven a failure as a means to this end, because, while operative in the reduction of friction, they are unable to withstand the strain of the load to which the jack is subjected. Beveled rollers commensurate with the bearing-surfaces have been suggested; but their operation was not entirely satisfactory, because, among other things, they tend to move endwise.

It is the object of the present invention to obviate the above-described defects and disadvantages and to provide a jack in which the friction shall be reduced, but which shall nevertheless be able to bear or carry the necessary load without destruction of any of its parts.

To this end the invention comprises the improvements to be presently described and finally claimed.

The nature, characteristic features, and scope of the invention will be more fully understood from the following description, taken in connection with the accompanying drawings, forming part hereof, and in which

Figure 1 is a side view, partly in section, illustrating a jack embodying features of the invention; and Fig. 2 is a top or plan view, drawn to an enlarged scale, of the roller-bearing.

In the drawings, 1 represents the rollers, which serve to reduce friction and at the same time are strong enough to carry the load. They may obviously be variously shaped so long as they are generally cylindrical in form, 45 which of course includes a slight taper, but

excludes balls. The rollers are shown as interposed between suitable hard washers 3 and 4. The cylindrical rollers are arranged end to end, so as to be revoluble independently of each other in radially-arranged openings 50 formed in the cage 2. The cylindrical form of the rollers imparts great strength and does not give rise to any tendency to endwise motion, and the fact that the rollers are each shorter than the bearing and are arranged end 55 to end permits them to revolve at different rates of speed, those nearest the edge going fastest, so that there is no undue grinding or slipping action. The washer 4 is shown as supporting the upper and movable part 5 of 60 the jack, and the washer 3 is shown as secured to the lifting-screw 6 of the jack by resting upon one of the miter-wheels, which is secured to the screw, as shown. The miter-wheels 7 and handle 8 afford means for revolving the 65 screw 6, which, acting through the intervention of the rollers 1, serves to lift the load and carry it, while the rollers minimize friction.

It will be obvious to those skilled in the art to which the invention relates that modifications may be made in details without departing from the spirit thereof. Hence the invention is not limited further than the prior state of the art may require; but,

Having thus described the nature and objects of my invention, what I claim as new, and desire to secure by Letters Patent, is

The combination of a lifting-jack having a screw and a movable part, a cage provided with radial openings, and cylindrical rollers 80 arranged end to end and disposed in groups in said radial openings, substantially as described.

In testimony whereof I have hereunto signed my name.

SAMUEL S. EVELAND.
